ABSTRACT

Covering or casing for unprotected risers adjacent interior walls, which consist of vertical supply or return pipes for steam, water, gas, sewer and the like, further to be used for covering of support posts for ceiling beams, horizontal pipe lines such as sprinkler pipes. The covering has adjustable spring clips for attaching the same on pipes of various sizes.

COVERING FOR RISER OR THE LIKE

BACKGROUND OF THE INVENTION

The invention refers to coverings, casings or enclosures for pipe lines, risers or other construction and building members or elements usually of substantially round sections. Risers and pipe lines are frequently found in buildings running adjacent walls or along ceilings, which must be protected or covered for various reasons, because they carry live steam, gas, hot water and the like fluids and because they do not present a pleasant sight. Permanent coverings for risers and pipe lines are known for insulating purposes, or these elements may be covered by masonry or by wooden boards, plywood or the like building material. None of these coverings are actually satisfactory because they are cumbersome, require considerable work to install, and they have to be disassembled or destroyed in case the covered risers or pipe lines have to be repaired or alterations have to be made. These conditions and disadvantages pose a problem, for which this invention presents a solution.

SUMMARY

The invention consists in such novel features, construction arrangements, combination of parts and improvements as may be shown and described in connection with the device herein disclosed by way of examples only and as illustrative of preferred embodiments. The invention essentially comprises longitudinal sections, elements or members substantially U-shaped or curved in section, and preferably made of sheet metal, but which may be cast from any other material suitable for covering the riser or pipe line as well as providing an embellishment therefor. Pairs of spring clips are attached to the inside of the flanges of the elements or members so that they can be easily attached to the risers, the clips being adjustably fastened thereto so that they can be applied to risers, pipes or round posts of various diameters.

Objects and advantages of the invention will be set forth in part hereafter and in part will be obvious herefrom or may be learned by practicing the invention, the same being realized and attained by means of the instrumentalities and combinations pointed out in the appended claims.

It is an object of the present invention to provide coverings or casings, or risers, pipe lines or the like cylindrically shaped building elements, which are aesthetic as well as being utilitarian in purpose.

Another object of the invention is to provide coverings for risers, which are constructed so as to be easily attached to the risers without special tools and to be easily removed in case the risers require repair or alteration.

A further object of the invention is to provide coverings for risers, which have attachment clips which can be adapted to accommodate risers of various diameters.

Yet another object of the invention is to provide coverings for risers, which can be used for both insulation and mechanical protection of the risers.

Various further and more specific purposes, features and advantages will clearly appear from the detailed description given below taken in connection with the accompanying drawing which forms part of this specifi-

cation and illustrates merely by way of example, certain embodiments of the device of the invention.

BRIEF DESCRIPTION OF THE DRAWING

In the following description and in the claims, parts will be identified by specific names for convenience, but such names are intended to be as generic in their application to similar parts as the art will permit. Like reference characters denote like parts in the several figures of the drawing, in which

FIG. 1 illustrates a covering or casing for risers or the like building elements, according to an embodiment of the invention viewed from the open, rear side thereof;

FIG. 2 is an end view of the covering shown in FIG. 1;

FIG. 3 is a side view of the lower end portion, partly broken off, of the covering shown in FIG. 1;

FIG. 4 is a side view of the upper end portion, partly broken off, of the covering shown in FIG. 1;

FIG. 5 is an enlarged view of a spring clip and the parts by which it is fastened on the wall of the covering; and

FIG. 6 illustrates on a reduced scale a modification in which the covering is curved in cross-section.

DESCRIPTION OF THE PREFERRED EMBODIMENTS

Referring now in more detail to the drawing illustrating preferred embodiments by which the invention may be realized, there is shown in FIG. 1 a channel-shaped covering or casing 10 for risers or the like building elements of a substantially cylindrical shape, such as support posts for ceilings, and for other pipe lines on or adjacent the inside walls or along ceilings of rooms. Covering 10 consists of individual elements, sections or members, each of which has its connecting walls or sides 10a, 10b, 10c at one end upset constituting a flared end 11. The other end 12 of each element or member is straight so that the individual elements or members 10 can be put together for any total length, as may be required. Each covering element 10 preferably consists of a strip of sheet metal which is bent to a U-shaped section. However, elements or sections 10 may be formed or cast of any other material suitable for covering the riser or pipe line as well as providing an embellishment therefor. Corners of the formed side flanges or walls 10a, 10c of the elements or sections 10 may be cut off, as shown at 13 in FIG. 4, for being fitted over a molding on a ceiling. Other adaptations to various other conditions may be made as easily as that shown in the example. Spring clips 15, 16 are fastened on the inside of the flanges or walls 10a, 10c of covering 10 opposite one another, respectively, in cooperative relationship. Clips 15, 16 are shaped in such manner that they can be snapped onto the riser 14 where they will be held in place by the action of the spring force. In order to accommodate the fitting of clips 15, 16 to risers of various diameters, they are held in engaged position against riser 14 by spaces 19 and carriage bolts 17 and screw nuts 18. Spacers 19 of suitable length are selected to maintain spacing clips 15, 16 the desired distance apart from one another to accommodate various diameters of risers 14. Horizontal slots 20 are provided in the side flanges 10a, 10c of covering sections 10 for carriage bolts 17 for adapting

the location of clips 15, 16 in relation to the distance of risers 14 from the wall of the building, as the case may be. Washers 17 are conventionally used.

The outside surface of covering 10 may be adequately embellished or decorated, or the material from which the sections 10 are formed, may be perforated in any suitable pattern. It is obvious that covers 10 may also serve as heat insulating means for steam pipes or the like insulating purposes. FIG. 6 shows a variation in shape of covering. The covering 10' may be curved in cross-section.

While the invention has been described and illustrated with respect to certain preferred examples which give satisfactory results, it will be understood by those skilled in the art after the principle of the invention, that various changes and modifications may be made without departing from the spirit and scope of the invention.

What is claimed is:

1. A cover for an unprotected vertical riser on an interior wall, said riser comprising a pipe providing means for supply and return respectively, for steam, gas, water, and the like fluids, said cover comprising a plurality of individual sections, each one of said sections comprising a substantially U-shaped channel 25

formed of sheet metal, said channel having a face side and two flange sides, at least one of said sides having a plurality of decoratively arranged perforations and at least two pairs of spring clips adjustably fastened on the inside of said flange sides, each of said pairs of clips disposed to be snapped on said riser.

5 2. A cover for riser according to claim 1, each of said pairs of clips comprising two independent spring members, said members adjustably fastened on said inside of said flange sides, respectively, cooperatively opposite one another, each of said members having two resilient wings for gripping said riser, each one of said wings having a curved shape.

3. A cover for a riser according to claim 2, and bolts having interchangeable spacers of different lengths for adjustably fastening said clips on risers having different diameters.

4. A cover for riser according to claim 3, and said side flanges of said channels having slots disposed substantially at right angles to the longitudinal axis of said channels, said slots disposed for fastening said bolts therein for adapting the position of said cover according to the distance of said riser from said wall.
